UNITED STATES PATENT OFFICE.

JOHN B. ATWOOD, OF PITTSBURGH, PENNSYLVANIA.

RAIL-FASTENER.

1,091,790.

Specification of Letters Patent. Patented Mar. 31, 1914.

Application filed December 17, 1912. Serial No. 737,355.

To all whom it may concern:

Be it known that I, JOHN B. ATWOOD, a citizen of the United States, and resident of Pittsburgh, in the county of Allegheny and State of Pennsylvania, have invented 5 a new and useful Improvement in Rail-Fasteners; and I do hereby declare the following to be a full, clear, and exact description thereof.

10 My invention relates to rail fasteners, and is particularly concerned with a device of this character for securing railway rails on metal ties.

One object of the invention is to provide 15 simple means by which the rail may be quickly and securely fastened to the tie.

A further object is to provide means by 20 which the rail may be readily detached, and by which new fasteners may be quickly substituted whenever necessary, while the rail maintains the same relative position with respect to the tie and with respect to the opposite rail.

25 A further object is to provide a fastener whereby the rail will be clamped to the tie against both lateral and longitudinal movement thereon, and a further object is to provide means in which the driving home of a fastening pin or spike will impart a 30 slight rotary movement to the fastening member proper by which the latter will clamp the rail and tie more effectually.

With these objects in view, the invention 35 consists in a construction and arrangement of parts preferred embodiments of which are illustrated in the accompanying drawings, in which—

Figure 1 is a fragmentary plan view of a 40 rail and tie showing the fastening device in conjunction therewith; Fig. 2 is a view taken transversely of the rail showing the tie and fastening device in elevation; Fig. 3 is a sectional view on the line 3—3 Fig. 1; Fig. 4 is a perspective view of the clamping 45 plate; Fig. 5 is a horizontal sectional view through the clip member, and Fig. 6 shows a modified form of fastening pin.

In the drawing, 1 indicates the rail, 2 an ordinary metallic tie preferably having the 50 flanges 3, 3. The fastener comprises a clamping plate 4 having the lug 5 adapted to engage the tie flange at one side and the second lug 6 arranged to engage the opposite side of the tie flange in staggered relation to the lug 5. The plate is also provided with the rail flange engaging lug 7 at the

end of the plate adjacent the tie flange lug 5. Arranged at the opposite end of the clamping plate on the same side thereof, as the lug 5, is an extension 8 having an aperture 9 therein to receive a fastening pin as hereinafter described. This extension 8 is arranged at an angle of substantially 45° through the side edge of the plate, and is shaped to receive a fastening clip as hereafter described. This clip comprises a body portion 10 having a passage 11 therethrough, whereby the clip may be slipped over the extension 8 of the clamping plate. The upper portion of the clip has a rail engaging 70 lug 12 and the lower portion has a tie flange engaging lug 13 extending in a direction substantially at right angles to the rail engaging lug. The rail engaging lug has a shoulder 14 to engage the side of the rail 75 flange to the flange engaging lug as a shoulder 15 to engage the side of the tie flange. The aperture in the clip is preferably rectangular to receive a substantially rectangular fastening pin 16 formed preferably of 80 hardened steel tapered on all sides and having comparatively sharp corners. This pin is also provided with a head 16a whereby it may be withdrawn from fastening position by means of the usual claw bar. 85

In assembling the parts the clamping plate lugs 5 and 6 are slipped over the edges of the tie flange and the plate is brought into proper position for the mounting of the rail on the tie. The rail is then placed upon the clamping plate and the lug 7 of said clamping plate is slipped over its flange. The clip member 10 is then slipped over the extension 8 of the clamping plate until the lugs 12 and 13 of said clip member engage the 90 rail flange and tie flange respectively. The lower end of the fastening pin 16 is provided at one of its corners 17 with a cut away portion by which the end of the pin may be slipped readily into the aperture of the clip members and past the edges of the tie flange. The fastening pin is then given a sharp blow which causes the sharp corner of its shank to cut its way through the edge of the tie flange, thus forming a 95 notch or recess in the side of said flange whereby the pin maintains a fixed position 100 relatively to the tie.

The aperture in the clip member and in the extension 8 of the clamping plate are so 110 arranged relatively to the rail clamping lug of the plate and the rail and tie clamping

shoulders of the clip that when the wedge pin is driven home the plate lug and clip lugs 12 are drawn together upon the rail to clamp the same firmly in position. At the 5 same time the engagement of the fastening pin with the tie flange has a tendency to twist or rotate the clamping plate on the tie and consequently causes the tie engaging lugs 5 and 6 of said plate to firmly engage the 10 opposite sides of the tie flange. It will be noticed also that the rail engaging lug 7 of the plate and the rail engaging lug 12 of the clip are arranged in staggered relation. This has a tendency to twist the rail when 15 the pin is driven home which movement is counteracted by the fastening of the rail on the adjacent tie or ties and therefore results in a firmer clamping of the rail to the tie and clamping plates. This action also 20 effectually prevents creeping of the rail with respect to the clamping plate and tie. The thickness of the pin near its head is slightly in excess of the area of the aperture in the clip member, so that when the pin is driven 25 home its head does not come into close contact with the clip. This serves two purposes, first it enables the wedge shape of the pin to exert its full wedging action in proportion to the power of the blow with which the pin 30 is driven home and furthermore leaves the head of the pin spaced away from the clip so that a claw bar will be readily inserted under the head to facilitate withdrawing the head when desired.

35 In order to secure the fastening pin firmly in fastening position the lower or outer end of the pin when driven home may be given a lateral blow with the hammer by which it is bent out of alinement thus preventing ac- 40 cidental withdrawal of the pin. This bending of the lower end is facilitated also by the cutting away of the pin at 17 as de- scribed.

If desired, instead of arranging the aper- 45 tures in the clip and plate extension 8 at an angle to the edge of the tie flange these apertures may be arranged parallel thereto and so that their inner edges lie somewhat within the edge of the tie flange and the pin may 50 be provided on one of its flat sides with sharp cutting ridges adapted to cut into and notch the edge of the tie flange. In all cases, however, it is preferable that the apertures be oblong in shape and that the fastening 55 pin be thicker at one end than the other in cross section, so that the pin will invariably be driven home with its cutting corners or ribs in proper position to engage the tie flange. It is to be understood that when 60 the pin is provided with cutting ridges these ridges are cut away or tapered at the lower end so as to facilitate the initial insertion of the pin in the apertures. The aperture in the clip and plate extension may be arranged 65 to permit the pin to engage both the tie and

the rail flange when driven home. The rail may be insulated from the tie and fastening means as illustrated in my companion application Serial No. 737,354, filed Dec. 17, 1912.

70

While I have described the particular embodiment of my invention, it is to be understood that the same may be altered in details and relative arrangement of parts within the scope of the appended claims.

75

What I claim is:

1. In a rail fastener the combination with a tie, of a fastening clip adapted to be inserted in the angle between the tie and rail, said clip having a rail flange engaging lug and a tie engaging lug said lugs having apertures therein, an abutment upon the opposite side of said rail and means engaging said apertures to hold the lugs of the clip firmly in engagement with the rail and the tie respectively and to force the rail against said abutment.

80

2. In a rail fastener the combination with a tie of a fastening clip having a rail engaging lug at its upper side, and a tie engaging lug at its lower side at right angles to each other and adapted to be placed in the angle between the tie and rail said lugs having apertures therein, an abutment at the opposite side of the rail and a pin adapted to engage the apertures of said clip to hold the same firmly against said rail and tie and to force the rail against said abutment.

85

3. In a rail fastener the combination with a tie, of a fastening clip adapted to be placed at an angle of substantially 45° with respect to the rail and tie and within the angle between the rail and tie, said clip having a rail engaging lug and a tie engaging lug extending at right angles to each other, an abutment at the opposite side of the rail, apertures in said clip lugs adapted to receive a fastening pin whereby the clip may be clamped upon said rail and tie respectively, and the rail clamped between said clip and said abutment.

90

4. In a rail fastener, the combination with a tie, of a clamping plate having lugs adapted to engage the opposite sides of said tie in staggered relation and having a rail clamping lug, of a clip member having a rail engaging lug and a tie engaging lug and an aperture to receive a fastening pin, and a fastening pin adapted to pass through said aperture to engage the tie whereby the clamping plate will be given a slight rotary movement to cause its tie engaging lugs to firmly clamp the tie, said pin acting also to cause said rail lugs to firmly engage the rail.

105

5. In a rail fastener, the combination with a tie, of a clamping plate having tie engaging lugs and a rail engaging lug, an apertured clip member having a rail engaging

110

115

120

125

130

- lug and a tie engaging lug adapted to be placed in the angle between the tie and rail at an angle to both tie and rail and a fastening pin adapted to be driven through the 5 aperture in said clip member and having a sharp ridge to notch and engage the edge of the tie whereby said clamping plate may be firmly clamped to the tie and the rail firmly clamped between the clamping plate lug and 10 the clip lug.
6. In a rail fastener, the combination with a tie, of a clamping plate having means to engage the tie and rail respectively, a clip member having means to engage the tie and 15 rail respectively, and fastening means cooperating with said clip member to impart a slight twisting movement to said plate with respect to the tie and rail and to clamp the parts firmly together.
- 20 7. In a rail fastener, the combination with a tie, of a clamping plate having tie engaging and rail engaging means, a clip member having tie engaging means and rail engaging means and adapted to be placed in the 25 angle between the tie and rail at an angle to both tie and rail and on the opposite side of the rail from the rail engaging means of the clamping plate and fastening means to cause said clip member to impart a slight 30 rotary movement to said clamping plate with respect to the tie and rail to cause said plate to firmly engage the tie and to clamp the rail between the rail engaging lugs of 35 said plate and said clip member respectively.
8. In a rail fastener, the combination with a tie, of a clamping plate having opposite clamping lugs to engage the tie in staggered relation and having a lug to engage one side 40 of the rail flange, said plate having an extension at an angle of approximately 45° to its side edges provided with an aperture, an apertured clip member having a tie engaging lug and a rail engaging lug and 45 adapted to slip over said plate extension to bring its aperture substantially in register with the aperture of said extension, and a fastening pin adapted to pass through said clip member and extension and having a 50 sharp ridge adapted to engage and notch the edge of the tie to impart to said plate a slight rotary movement whereby the tie engaging means of said plate may firmly engage the tie and the rail may be firmly clamped between said plate lug and the lug 55 of said clip member.
9. In a rail fastener, the combination with a tie, of a clamping plate having tie engaging and rail engaging means, a clip member having tie engaging means and rail engaging means and adapted to be placed in the angle between the tie and rail at an angle to both tie and rail and on the opposite side of the rail from the rail engaging means of the clamping plate and fastening means to 60 cause said clip member to impart a slight rotary movement to said clamping plate with respect to the tie and rail to cause said plate to firmly engage the tie and to clamp the rail between the rail engaging lugs of 65 70 said plate and said clip member respectively, and means for retaining said fastening pin in fastening position.
10. In a rail fastener, the combination with a tie, of a clamping plate having opposite clamping lugs to engage the tie flange in staggered relation and having a lug to engage one side of the rail flange, said plate having an extension at an angle of 45° of 75 its side edges provided with an aperture an 80 apertured clip member having a tie engaging lug and a rail engaging lug and adapted to slip over said plate extension to bring its aperture in register with the aperture of an extension, and a fastening pin adapted 85 to pass through said clip member and extension and having a sharp ridge adapted to engage and notch the edge of the tie flange, to impart to said plate a slight rotary movement whereby the tie engaging 90 means of said plate may firmly engage the tie and the rail may be firmly clamped between said plate lug and the lug of said clip member, and means for retaining said pin in fastening position. 95
